A. GRUB

TOWEL CABINET

Filed Dec. 28, 1918

UNITED STATES PATENT OFFICE.

ALBERT GRUB, OF CHICAGO, ILLINOIS.

TOWEL CABINET.

Application filed December 26, 1918. Serial No. 268,603.

To all whom it may concern:

Be it known that I, ALBERT GRUB, a citizen of the United States, residing in the city of Chicago, county of Cook, and State of Illinois, have invented certain new and useful Improvements in Towel Cabinets, of which the following is a specification, reference being had to the accompanying drawings, forming a part thereof.

10 This invention relates to a towel cabinet of the type in which storage space for a quantity of clean towels is provided, and each towel is individually anchored to the cabinet in a manner permitting its removal from the storage space for use, but preventing the user from taking the towel away with him. The present invention also includes coin-operated means for controlling the release of towels from the storage space, together with other features and elements all hereinafter described and shown in the drawings, as indicated by the claims.

In the drawings:

Figure 1 is a front elevation of a towel cabinet embodying this invention with the front wall of the cabinet removed to reveal certain interior features of the device.

Figure 2 is a partial front elevation of the cabinet with the front wall in place but with a portion thereof broken away to show certain parts of the coin-controlled mechanism mounted on said wall.

Figure 3 is a transverse horizontal section taken as indicated at line, 3—3, on Figure 1.

Figure 4 is a detail section taken as indicated at line, 4—4, on Figure 2.

Figure 5 is a detail section taken as indicated at line, 5—5, on Figure 2.

Figure 6 is a vertical section taken as indicated at line, 6—6, on Figure 1.

Figure 7 is an enlarged detail view of a portion of the towel guide rods shown in Figure 6.

Figure 8 is a diagrammatic sectional view taken as indicated at line, 8—8, on Figure 7.

It may be understood that the towels used in conjunction with this cabinet are rectangular in form and each provided at about the middle of one side and near the margin with an eyelet preferably of metal or other fairly stiff material by which the towels are retained on a guide rod, 1, extending vertically in the cabinet. Thus en-

gaged with the rod, 1, a pile of towels is supported upon a shelf which is bifurcated or made into two parts, 2, 2, disposed at a convenient height from the floor to permit manipulation of the towel at the bottom of the pile. The rod, 1, extends vertically through the eyelet of the towel in the pile, and at a slight distance above the bifurcated shelf, 2, it bends forwardly at 3, as seen in Figures 6 and 7, this initial bend, 3, being fairly abrupt but slightly greater than a right angle. The rod extends forwardly only a short distance from the bend, 3, thence dips abruptly downward at 4, and then by a curve, 5, of larger radius than the curve, 3, connects with a horizontal portion, 6, extending midway between the two shelf portions, 2, 2, upon which the towels rest. At 7 the rod bends acutely downward and rearwardly for guiding the towels into the lower space which serves as a receptacle for them when they are soiled. It will be understood that the lowest towel of the pile is brought into use by drawing it forward along the guide rods from the bend, 3, to the bend, 7, at which substantially the entire area of the towel is exposed, and after being used in this position it is allowed to fall into the lower receptacle, guided along the part, 8.

Adjacent the bend, 3, there is secured to the rear wall, 9, a bifurcated towel-retaining bracket, 10, whose arms extend horizontally at opposite sides of the rod, being separated by a distance slightly greater than the diameter of one of the rigid eyelets with which each towel is provided. The bracket, 10, being positioned somewhat above the level of the shelf, 2, requires the rear edges of the towels in the pile to deflect upwardly and rearwardly from the supporting frame of the shelf, 2. The bend, 3, in the guide rod begins just below the upper plane of the retaining bracket, 10, but the weight of the pile of towels, or even the weight of one eyelet will cause the eyelet of the lowest towel in the pile to sag between the two arms of the bracket as indicated in Figure 8, thus giving this lowest eyelet an initial engagement with the bend, 3. As a result, if the forward edge of the towel be grasped, being accessible through an opening, 11, in the board, 12, at the front of the cabinet, and then if a forward pull be exerted on the towel, the eyelet of this

lowest towel will follow around the bend, 3, as indicated in dotted lines in Figure 7, and will travel also around the bends, 4 and 5, and along the horizontal section, 6, this 5 lowest towel sliding over the under surface of the next towel in the pile, and coming to a position of use at the bend, 7. As the eyelet twists around the bend, 3, its forward edge will press upwardly against the next 10 eyelet and against the lower surface of the next towel in the pile, preventing the latter from falling down between the arms of the bracket, 10, until the lowest towel has been withdrawn so far that there is no tendency for it to drag the next towel with it 15 along the guide rod. On the other hand, it would be impossible to withdraw two towels at one time, since the upper towel would have its eyelet engaged with a substantially vertical portion of the rod, 1, just preceding the bend, 3, and this upper eyelet having no initial engagement with the bend, 3, would have no tendency to slide 20 around it.

25 Preferably, for the sake of cleanliness, the towels supported on the bifurcated shelf, 2, are enclosed in a cabinet having having side walls, 13, a top, 14, and a front wall, 15, to the lower edge of which the door, 12, already 30 mentioned, is attached by spring hinges, 16, tending to hold it in closed position in the vertical plane of the wall, 15. When a towel is withdrawn from the bottom of the pile, being grasped through the opening, 11, in 35 the bottom of the door, 12, the latter swings yieldingly forward to permit the towel to pass between the rear face of the door, 12, and the front edge of the bifurcated shelf, 2, against which the door, 12, closes. If it is 40 desired to make such a cabinet yield a revenue for the use of each towel, the door, 12, may be positively locked against the front edge of the shelf, 2, thus tending to effectively prevent removal of any towels 45 through the opening, 11, and the lock device may be coin-controlled by a mechanism about to be described.

The lock consists of a rigid hook or catch, 17, secured to the rear face of the door, 50 12, and engaged by a locking finger, 18, on the end of a lever, 19, pivoted at 20, to the fixed front wall, 15, and carrying on its 55 other arm a coin receiver, 20, which normally stands at the discharge end of a coin chute, 21, mounted in the wall, 15. The weight of a coin arriving in the receptacle, 20, will swing the lever, 19, about its pivot, 20, disengaging the finger, 18, from the catch, 17, and thus permitting the door, 11, to swing 60 away from the front edge of the shelf, 2, to allow withdrawal of the towel from the bottom of the pile in a manner already described. As the lever, 19, swings downwardly, the coin is retained in the receiver, 65 20, by a guide rail, 22, but as the lever

strikes the lower stop, 23, the coin will be retained in the receiver, 20, against gravity discharge therefrom into the receiving chute, 24, which leads to the coin box, 25, unless by that instant the lowest towel has 70 already been withdrawn partially from its normal position in the pile. A vertically 75 slideable gate, 26, forming a continuation of the guide rail, 22, is disposed adjacent the upper end of the chute, 24, so that until a 80 towel has been withdrawn, the weight of the coin in the receiver, 20, will hold the lever, 19, with its locking finger, 18, out of engagement with the catch, 17, on the door, 12, whereas if the coin were permitted 85 to be discharged immediately, the lever, 19, being counter-balanced by the weight, 27, might swing back to locking position before the depositor of the coin had withdrawn the towel for which he had paid. 85

But as the towel is withdrawn along the rod, 6, the eyelet of the towel at its rear edge will engage a contact member, 28, on a swinging arch or lever, 29, fulcrumed in the lower portion of the cabinet, and connected by 90 suitable linkage with the slideable gate member, 26, for moving the latter upwardly as the towel is withdrawn forward along the rod, 6, thereby permitting the coin in the receiver, 20, to pass into the chute, 24, and coin box, 25, and permitting the locking lever, 19, to return to locking position, as shown in full line in Figure 2. If at the instant the lever, 19, returns to locking position, the door, 12, has not already been swung shut 100 by its spring hinges, 16, the catch, 17, will nevertheless be properly engaged with the locking finger, 18, when the door, 12, is closed, since the catch member is provided with a slanted cam face, 30, which will momentarily deflect the locking lever, 19, and finger, 18, from locking position to permit closing of the door, 12, while gravity acting through the counter-weight, 27, will return the locking finger, 18, for engaging the hook, 17. The towel-controlled linkage which releases the coin from the receiver, 20, is automatically returned to normal position by a retracting spring, 31, seen in Figure 6. 105

110 I claim:

1. In a device of the character described, a support for a pile of towels, a rod arranged above said support in position to extend through registering openings in the towels, said rod having a part at its lower end bent laterally in the vicinity of the towel-supporting surface of said support, and means extending from the front end of said part to the front end of said support for retaining the towels after they have been 115 drawn laterally. 120

2. In a device of the character described, a support for a pile of towels, and a towel retainer extending downwardly from a point above the support into the vicinity of the 125 130

towel-supporting surface of the support and then laterally toward one edge of the support and then downwardly.

3. In a device of the character described, 5 an upright rod having its lower end bent laterally so as to form a rounded heel, and means for supporting a pile of towels strung on said rod in such position that the lowermost towel has a part yieldably held in engagement with said heel so as to permit that 10 towel to be drawn along the lateral portion of the rod by a pull in the direction of said lateral portion without danger of giving to the next succeeding towel a simultaneous 15 similar movement.

4. In a device of the character described, an upright rod having its lower end bent laterally so as to form a rounded heel, means for supporting a pile of towels strung on 20 said rod in such position that the lowermost towel has a part in engagement with said heel so as to permit that towel to be drawn along the lateral portion of the rod by a pull in the direction of said lateral portion, and 25 means extending from the end of said lateral portion for retaining the towels after they have been drawn laterally.

5. In a device of the character described, an upright rod having its lower end bent 30 laterally, a support for a pile of towels strung on said rod having its upper surface lying just below the laterally-bent portion of the rod, said support having a slot extending through the same from one edge 35 into the vicinity of said rod, and means extending from the end of the lateral portion of the rod through said slot toward said edge of the support.

6. In a device of the character described, 40 a support for a pile of towels having a slot extending inwardly from one edge thereof, an upright rod arranged above the support beyond the inner end of the slot, said rod having a part bent laterally just above the 45 support and then downwardly into said slot.

7. In a device of the character described, a support for a pile of towels having a slot 50 extending inwardly from one edge thereof, an upright rod arranged above the support beyond the inner end of the slot, said rod having a part bent laterally in the vicinity of the top of the support and then downwardly into the slot and laterally through the same to said edge of the support.

8. In a device of the character described, 55 a support for a pile of towels having a slot extending inwardly from one edge thereof, a rod arranged above said support in position to extend through registering openings in 60 the towels, said rod having a part of its lower end bent laterally in the vicinity of said slot, and means extending from the free end of said part into and along the general direction of the slot to permit the lowermost

towel of the pile to be drawn off of said support. 65

9. In a device of the character described, a support for a pile of towels having slots extending inwardly from one edge through the same, and a towel retaining member extending downwardly from a point above the support into the vicinity of the towel supporting surface of the support and then laterally through said slot and then downwardly. 70 75

10. In a towel cabinet, a bifurcated shelf to support a pile of towels, a guide rod to engage an eyelet in each towel, and having a bent portion disposed adjacent the rear of the shelf with a part extending upwardly 80 therefrom, and a part directed forwardly between the two arms of the shelf, together with a bifurcated towel retainer adjacent the upright part of the rod with its upper surface in a plane cutting the rod substantially at the point where said bent portion emerges into said upright part, said retainer being disposed above the plane of the shelf and extending forward only slightly beyond the upright part of the rod. 85 90

11. In the combination defined in claim 10, the opening in said bifurcated retainer adjacent the rod being wide enough to permit the eyeletted portion of the bottom towel of the pile to sag through said retainer 95 into initial engagement with the bend of the rod.

12. In a towel cabinet comprising a horizontal supporting shelf for a pile of towels with rear and side walls to enclose said pile, 100 a towel-retaining guide-rod within the cabinet extending forwardly along the shelf permitting withdrawal of the towels only past the forward edge of said shelf; a door at the front side of the cabinet engaging the front edge of the shelf in closed position and hinged above the shelf for swinging of its lower edge out of such engagement to permit withdrawal of the bottom towel of the pile, together with a locking device to retain 105 said door against the shelf. 110

13. In the combination defined in claim 12, said locking device including a yielding catch; coin-controlled means for releasing the catch, and means operable by the withdrawal of a towel for returning the catch to locking position. 115

14. In the combination defined in claim 12, said door having a notch in its lower edge adjacent the guide rod to give access 120 to the bottom towel of the pile when the door stands in engagement with the edge of a shelf.

In testimony whereof, I have hereunto set my hand at Chicago, Illinois, this 7th day 125 of December, 1918.

ALBERT GRUB.
